US00D710380S

(12) **United States Design Patent**
Kyung-Dae et al.

(10) **Patent No.:** **US D710,380 S**
(45) **Date of Patent:** **** Aug. 5, 2014**

(54) **PORTABLE ELECTRONIC DEVICE
DISPLAYING GI AND GUI**

(71) Applicant: **Samsung Electronics Co., Ltd.,**
Suwon-si (KR)

(72) Inventors: **Park Kyung-Dae**, Seoul (KR); **Jeon
Heekyung**, Seoul (KR)

(73) Assignee: **Samsung Electronics Co., Ltd.,**
Suwon-Si (KR)

(**) Term: **14 Years**

(21) Appl. No.: **29/445,220**

(22) Filed: **Feb. 8, 2013**

(30) **Foreign Application Priority Data**

Aug. 29, 2012 (KR) 30-2012-0041623

(51) **LOC (10) Cl.** **14-04**
(52) **U.S. Cl.**

USPC **D14/489**

(58) **Field of Classification Search**

USPC D14/485-495; 715/719, 786, 835, 810,
715/763, 739, 733, 762; 705/15; D11/169,

(57) **CLAIM**

The ornamental design for a portable electronic device displaying GI and GUI, as shown and described.

DESCRIPTION

The FIGURE is a front-side view of a portable electronic device displaying GI and GUI showing our new design.

The broken lines illustrating portions of the display screen and the portable electronic device form no part of the claimed design.

1 Claim, 1 Drawing Sheet
